POWER SHOVEL

Trevor Davidson, Milwaukee, Wis., assignor to
 Bucyrus-Erie Company, South Milwaukee, Wis.,
 a corporation of Delaware

Application November 15, 1928, Serial No. 319,600

7 Claims. (Cl. 214—145)

My invention relates to new and useful improvements in power shovels.

Power-shovels are well known in the excavating art. They consist in a main frame, with a boom pivoted at its foot to the frame and suspended by means of tension members connecting its outer end to an elevated point on the frame. About half way up the boom is a shipper-shaft, on which a dipper-handle reciprocates and swings 10 in a vertical plane. Various alternative means are employed to accomplish this swinging and reciprocating, but these means are not involved in the present invention. At the outer end of the handle is a digging dipper.

15 The better practice in building such power-shovels is to make the handle with two legs, straddling the boom, and to join these two legs by a torsion-box, such for instance, as is shown in Patent No. 1,599,630, to Bager and Lehman.

20 In very large shovels, however, it has been found that the digging strains are too great for such a torsion-box to bear; and accordingly, in the case of very large shovels, it has been considered by others necessary to revert to the ancient and inferior design of a dipper handle of one leg or two closely placed legs, passing through an opening in a divided boom.

25 The principal object of my invention is to provide a novel form of construction, so that the digging strains will be transmitted to those parts of the machine best able to stand them, and be resisted at such points; and thus permit the retention of the advantages of a divided dipper handle straddling the boom. To accomplish this end, I combine three features, namely: (1) the two boom-suspension cables, hereinafter described; (2) the twin hoist-ropes, hereinafter described; and (3) a trussed dipper handle, which rigidly resists relative motion of the legs in the plane thereof, while still permitting the warping of that plane. I claim as novel the combining of these three features, and also the third feature in itself. All three features cooperate to the desired end.

30 Further objects and advantages of my invention will be readily evident, as the description progresses.

The invention consists in the novel parts, and 35 in the combinations and arrangements thereof, which are defined in the appended claims; and of which one embodiment is exemplified in the accompanying drawings, which are hereinafter particularly described and explained.

40 Throughout the description, the same reference

number is applied to the same member or to similar members.

Figure 1 is a side elevation of so much of a power shovel as is necessary to illustrate my invention.

Figure 2 is a plan view of the dipper-handle of Figure 1.

Figure 3 is an enlarged side elevation of this handle taken on the line 3—3 of Figure 2.

Referring to Figure 1, it will be seen that 45 65 the main frame of a power shovel, supporting the boom 12, the A-frame 13, and the double-drum dipper-hoist winch 14.

On a bracket 15 on the boom 12 is mounted a shipper shaft 16, carrying two saddle-blocks 17, 70 through which the dipper-handle 18 reciprocates, and which pivot about the shipper shaft 16, thus enabling the dipper-handle 18 to swing in the vertical plane which contains the boom 12.

75 There are two boom-suspension cables, of which only one 19 is shown. The other is symmetrically placed on the other side of the boom, and is reeved identically to the one shown. Each passes from an anchorage 20 on the end of the shipper shaft 16, thence around a sheave 21 near one 80 extreme side of the apex of the A-frame 13, thence around a sheave 22 at the point of the boom, and thence back to an anchorage 23 adjacent the sheave 21.

85 From the double-drum winch 14 run two ropes, of which only one 24 is shown. The other is symmetrically placed on the other side of the boom, and is reeved identically to the one shown. Each passes from the winch 14 over a sheave 25 at the point of the boom to an anchorage on one of 90 the rear corners of the dipper 26, which is carried by the dipper-handle 18.

95 Turning now to Figure 2, it will be seen that the dipper-handle, therein illustrated, consists in two widely laterally spaced legs 27 and 28, which may be of any desired construction, preferably built up of structural steel, the details of the construction not being considered material to show or describe herein.

100 Figure 3 shows a rack 29, one such rack being carried by each of these legs for engagement with a pinion 30 carried by the shipper shaft 16.

Reverting to Figure 2, each of the legs 27 and 28 terminates at its forward end in a casting 31 or 32, having lugs 33 for fastening to the upper 105 rear corner of the dipper 26, and lugs 34 (see Figures 1 and 3) for fastening to the dipper braces 35. Other castings 36 and 37 are also provided, as abutments for some of the bars to be hereinafter mentioned.

The two handle legs are secured together by three adjustable cross-bars 38, 39 and 40, in spacers 45, 46 and 47, and by four diagonal adjustable bars 41, 42, 43 and 44.

- 5 The diagonal bars serve as swiveled tension members, as will now be explained. Ropes or chains might be substituted therefor, or compression members if sturdy enough to resist buckling, but my construction as illustrated is preferred.
- 10 Consider diagonal bar 41, for example. One end thereof is screwed into clevis 48, which is pivoted to casting 32. The bar is locked to clevis 48 by means of lock nut 49. The other end of the bar is cylindrical and passes loosely through a cylindrical orifice in clevis 50, which clevis is pivoted to casting 36. The bar is held for tension only against the clevis by double nuts 51, double nuts being employed so that these nuts do not bind on clevis 50, which would prevent 20 swiveling of bar 41 in its cylindrical hole in the clevis. Thus there is nothing to resist thrust by the bar nor turning of the bar with respect to its clevis. The other three diagonal bars are similarly arranged.
- 25 The cross-bars, in their spacers, serve as columns, and are essentially swiveled compression members, as will now be explained. Each spacer, as for example 45, bears loosely against the castings at its ends, such as 36 and 37, so that it is free to turn with respect thereto. The ends of each cross bar, such as 38, pass loosely through cylindrical holes in the castings, such as 36 and 37, and the dipper handle legs 27 and 28. Double nuts are used at the end of each cross bar in the same manner and for the same purpose as described above with respect to double nuts 51 on diagonal bar 41. Thus the two handle legs are free to swivel on the ends of the cross spacers, which thus serve as swiveled compression members.

In the claims, when I employ the word "swiveled", I intend thereby: "pivoted for rotation about the long axis of the part described as swiveled."

- 45 It will readily be seen that all the bars, taken together, constitute a truss, which effectively resists any relative lengthwise shifting of the two handle legs, while at the same time permitting the handle as a whole to twist. The handle is thus like a horizontal strip of metal, which can twist but is not otherwise deformable.

50 Thus any tendency to sidewise motion of the dipper is transmitted by the handle, acting as a unit, through the racks 29 and pinions 30 to the shipper shaft 16, and thence by the twin cables 24 to the A-frame 13, and there resisted; whereas any twist imparted to the handle is not resisted thereby but is transmitted by the twin hoist-ropes 24, to the winch 14, on the main base 11, and there resisted.

55 Having now particularly described and illustrated one exemplification of my invention, I wish to be understood as not thereby limiting myself to the particular form shown, except in so far as such limitations are specified in the accompanying claims.

I claim:

- 60 1. In a power-shovel, having an A-frame, a boom, a shipper-shaft mounted at a point intermediate the ends of the boom, and a dipper, the combination of: a two-leg dipper-handle straddling the boom, the legs being secured to the dipper at widely spaced points; a plurality of swiveled bars in spacers connecting these legs and substantially perpendicular thereto; a plurality

of diagonal swiveled tension bars connecting these legs; all bars lying substantially in the same plane; two racks, one being on each handle-leg; two pinions on the shipper-shaft, one engaging each rack; two boom-suspension cables, passing from the A-frame to widely spaced points on the shipper-shaft; and two hoist-cables, passing over twin sheaves at the outer end of the boom to widely spaced anchorages on the dipper.

- 80 2. In a power-shovel, having an A-frame, a boom, a shipper-shaft mounted at a point intermediate the ends of the boom, and a dipper, the combination of: a two-leg dipper-handle straddling the boom, the legs being secured to the dipper at widely spaced points; a plurality of struts connecting these legs and substantially perpendicular thereto; a plurality of diagonal tension members connecting these legs; all struts and tension members lying substantially in the same plane; two racks, one being on each handle-member; two pinions on the shipper-shaft, one engaging each rack; two boom-suspension cables, passing from the A-frame to widely spaced points on the shipper-shaft; and two hoist cables, passing over twin sheaves at the outer end of the boom to widely spaced anchorages on the dipper.

- 85 3. In a power-shovel, having an A-frame, a boom, a shipper-shaft mounted at a point intermediate the ends of the boom, and a dipper, the combination of: a two-leg dipper-handle straddling the boom, the legs being secured to the dipper at widely spaced points; a plurality of members connecting these legs and substantially perpendicular thereto; a plurality of diagonal members connecting these legs; all such members of both classes lying substantially in the same plane; two racks, one being on each handle-leg; two pinions on the shipper shaft, one engaging each rack; two boom-suspension cables, passing from the A-frame to widely spaced points on the shipper 105 shaft; and two hoist cables, passing over twin sheaves at the outer end of the boom to widely spaced anchorages on the dipper.

- 110 4. In a power-shovel, having an A-frame, a boom, a shipper-shaft mounted at a point intermediate the ends of the boom, and a dipper, the combination of: a two-leg dipper-handle straddling the boom, the legs being secured to the dipper at widely spaced points; a plurality of members connecting these legs, forming with the legs a truss, rigidly resisting relative motion of the legs in the plane thereof, and yet permitting the warping of the plane; two racks, one being on each handle-leg; two pinions on the shipper-shaft, one engaging each rack; two boom-suspension cables, passing from the A-frame to widely spaced points on the shipper-shaft; and two hoist-cables, passing over twin sheaves at the outer end of the boom to widely spaced anchorages on the dipper.

- 115 5. In a power-shovel, having a boom, a shipper-shaft mounted at a point intermediate the ends of the boom, and a dipper, the combination of: a two-leg dipper-handle straddling the boom, the legs being secured to the dipper at widely spaced 120 points; a plurality of swiveled bars in spacers connecting these legs and substantially perpendicular thereto; and a plurality of diagonal swiveled tension bars connecting these legs; all bars lying substantially in the same plane.

- 125 6. In a dipper-handle, the combination of: two laterally widely spaced structural legs; two racks, one being carried by each of said legs; two handle-end castings, one being carried by each of said legs, each casting being provided 130

145

150

with lugs for attachment to a dipper, and lugs for attachment to tension and compression members; swiveled bars in spacers connecting these legs and substantially perpendicular thereto; and a plurality of diagonal swiveled tension bars connecting these legs; all bars lying substantially in the same plane.

7. In a power-shovel, having an A-frame, a boom, a shipper-shaft mounted at a point intermediate the ends of the boom, and a dipper, the combination of: a two-leg dipper-handle strad-

ding the boom, the legs being secured to the dipper at widely spaced points; means connecting these legs, and rigidly resisting relative motion of the legs in the plane thereof, while permitting warping of the plane; two boom-suspension cables, passing from the A-frame to widely spaced points on the shipper-shaft; and two hoist cables, passing over twin sheaves at the outer end of the boom to widely spaced anchorages on the dipper.
